M. J. BRIGGS.

THERMOSTAT.

APPLICATION FILED OCT. 22, 1908.

992,542.

Patented May 16, 1911.

UNITED STATES PATENT OFFICE.

MELANCTHON J. BRIGGS, OF PHILADELPHIA, PENNSYLVANIA.

THERMOSTAT.

992,542.

Specification of Letters Patent.

Patented May 16, 1911.

Application filed October 22, 1908. Serial No. 458,990.

To all whom it may concern:

Be it known that I, MELANCTHON J. BRIGGS, a citizen of the United States, residing in the city and county of Philadelphia, State of Pennsylvania, have invented a new and useful Thermostat, of which the following is a specification.

My invention is concerned with a new form of electrical thermostat, such as is employed in a fire alarm circuit to indicate a rise in temperature to or beyond certain predetermined degrees.

My invention is designed as an improvement upon my former invention of a thermostat, particularly described in the specification therefor, filed June 8th, 1908, Serial No. 437,463, and is to be used only in connection with, and inclosed in, a hermetically sealed tube or case, which tube or case, will 20 constitute the expansible member of the thermostat, as described in the said specification.

The object of my invention is to so improve my said former invention, as to have 25 the means of both closing and opening the electrical circuits, actuated directly by the expansible member, without the aid of a spring or other device.

My invention is illustrated in the accompanying drawings in which—

Figure 1, represents the front elevation of the interior mechanism of a thermostat embodying my invention, the casing being shown in section and Fig. 2, represents a 35 section on line α — α of Fig. 1.

The same figures designate the same parts throughout the drawings.

For the purpose of illustrating my invention, I have shown in said drawings, one 40 form thereof, which is at present preferred by me, since the same has been found in practice to give satisfactory and reliable results, although it is to be understood that the various instrumentalities of which my 45 invention consists, can be variously arranged and organized and that it is not limited to the precise arrangement and organization of those instrumentalities, as herein shown and described.

50 The expansible member 1 of my thermostat, consists of an elongated tube or case, so constructed as to inclose all the other operative parts of the thermostat, except the head of the adjusting screw, in a hermetically sealed compartment, so that the parts 55 so inclosed may not be corroded, impaired

or affected by gases, moisture or dust in the atmosphere surrounding the thermostat, while the expansible member is itself so exposed as to be immediately affected by any 60 changes in the temperature of such atmosphere; said expansible member 1, may be of any metal or substance which readily expands with heat and contracts with cold, but preferably of zinc or brass, and it may be 65 constructed in any suitable forms, but preferably in the form of a cylindrical tube, or an elongated rectangular case, with the ends hermetically closed with the same material.

An adjustable base 2, preferably made of 70 a thin but rigid piece of wood or porcelain, or some other non-conducting material, but slightly affected by changes of temperature, extends nearly the entire length of the inside of said expansible member 1, and 75 should fit so loosely therein as to be readily moved longitudinally by the adjusting screw 4. Said base 2, has a metal block 6, rigidly affixed to one end thereof, which block 6 is perforated by a threaded hole 5, fitting the 80 adjusting screw 4, which passes through said hole 5, and holds that end of said base 2 firmly in position. Adjacent to the other end of said base 2, and rigidly affixed thereto, is a metal plate 10.

The lever conductor 3, is pivotally attached to said metal plate 10, by its fulcrum pin 12, and the short arm of said lever conductor is pivotally attached to the metal block 9, by the pivot pin 11, the said block 9, 90 being rigidly attached to the end piece 8, of the expansible member 2, and extending through the said end piece 8, to the binding post 21. The long arm of said lever conductor 3, extends down so as to engage the 95 flexible spring contact 19, and to press the same against the contact 20.

The adjusting screw 4, passes through a closely fitting round hole in the center of the end piece 7, of the expansible member 1, and 100 has a collar 18, so brazed or soldered on to said adjusting screw 4, as to preclude any longitudinal movement thereof; the threaded end of said adjusting screw 4, passes through the threaded hole 5, in the block 6, 105 affixed to the said base 2, holding the end of said base 2, firmly in position. By turning said adjusting screw 4, to the right or left, the base 2, is moved longitudinally, which forces the long arm of said lever conductor 110 3, toward or away from the said contact 19. The flexible spring contact 19, is affixed to

the base 2, by the metallic pin 13, which extends through said base 2, and is attached to the insulated wire 15; said contact consists of a flexible spring which will yield to pressure of the long arm of the lever conductor 3, and springs back to its normal position when such pressure is removed.

The flexible spring contact 20, is affixed to said base 2, by the metallic pin 14, which extends through said base 2, and is attached to the insulated wire 16. The contact 20, is so placed in reference to the contact 19, that when the temperature increases a predetermined number of degrees above that at which the said lever conductor 3, engages said contact 19, said contact 19, is forced by the continued pressure of said lever conductor 3, against said contact 20, thus closing the second circuit. The wire 17 is attached to the binding post 21, extending thence to the positive pole of an electric battery.

The insulated wire 15, is attached to the metallic pin 13, and extends through the hermetically sealed hole 22, in the end 8, of the expandible member 1, and thence, through the armatures of desired signals, to the negative pole of said electric battery. The insulated wire 16, is attached to the metallic pin 14, and extends through the said hermetically sealed hole 22, and thence, through the armatures of the distinctive signals of the second circuit, to the negative pole of said electric battery. Upon the exterior of the end 7, of said expandible member 1, is placed a dial plate upon which is laid off a scale, so spaced that the movement of the indicating arm attached to the head of the adjusting screw 4, one space on said scale, makes a change of 5 degrees in the temperature required to close the first circuit.

The operation of my device will, it is believed, be perfectly clear from the foregoing; in practice, the thermostat may be adjusted, by means of said adjusting screw 4, to close the first circuit at any predetermined degree of temperature. When the thermostat is exposed to that degree of heat, the expandible member 1, will be so extended as to carry the short arm of the lever conductor 3, up, and the fulcrum 12, on the base 2, being fixed, and the long arm of the lever conductor 3, is thrown to the right and against the electrical contact 19, thus closing the first circuit. Should the temperature continue to increase, the pressure of the long arm of said lever conductor 3, will force the flexible spring 19, toward the contact 20, and when it reaches the degree at which contact 20 is set, said contact 19, will engage the contact 20, thus closing the second circuit. A falling temperature will cause a contraction or shortening of the expandible member 1, thus causing the block 9, to force the short arm of the lever conductor 3,

downward, and the long arm thereof to the left, and away from the contact 19; both of said contacts 19 and 20 will then spring back to their normal positions, as soon as the pressure of the long arm of said lever conductor 3, is thus removed.

Having now fully demonstrated my invention, what I deem as new and desire to secure by Letters Patent is—

1. In a device of the character described, the combination with an expandible member, consisting of an hermetically closed tube or case, an adjustable base inclosed therein, a lever conductor pivotally attached to the said base, one arm of said lever conductor pivotally attached to said expandible member, an electrical contact within said expandible member rigidly affixed to said base in the path of the other arm of said lever conductor, and external means for adjusting the thermostat by moving said base longitudinally.

2. In a device of the character described, the combination with an expandible member, consisting of an hermetically closed tube, an adjustable base inclosed therein, a lever conductor having its fulcrum rigidly attached to said base, one arm of said lever conductor pivotally attached to the said expandible member, a flexible spring electrical contact within said expandible member attached to said base in the path of the other arm of said lever conductor, a second electrical contact within said expandible member with which the said flexible spring contact will engage at a predetermined increase of temperature, whereby a second distinct signal may be given, and external means for adjusting the thermostat by moving said base longitudinally.

3. In a device of the character described, the combination with an expandible member, consisting of an hermetically closed tube or case, an adjustable base inclosed therein, a lever conductor pivoted upon a fulcrum rigidly attached to said base, a block rigidly attached to said expandible member, one arm of said lever conductor pivotally attached to said block, two electrical contacts within said expandible member attached to said base in the path of the other arm of said lever conductor, by which two distinct circuits may be successively closed, and external means for adjusting said thermostat by moving said base longitudinally.

4. In a device of the character described, the combination with an expandible member, consisting of an hermetically closed tube or case, an adjustable base inclosed therein, a lever conductor pivoted upon a fulcrum rigidly attached to said base, a block rigidly attached to said expandible member, one arm of said lever conductor pivotally attached to said block, an electrical contact within

said expandible member independent of said lever conductor and attached to said base in the path of the other arm of said lever conductor, and an adjusting screw anchored 5 in the end piece of said expandible member, by which said base is moved longitudinally.

In testimony whereof, I hereby subscribe

this specification in the presence of two witnesses.

MELANCTHON J. BRIGGS.
